THREAD CUTTING AND CLAMPING
MECHANISM

John J. Stanley, Packanack Lake, N. J., assignor,
by mesne assignments, to Steel and Alloy Tank
Company, Newark, N. J., a corporation of New
Jersey

Application March 23, 1950, Serial No. 151,417

15 Claims. (Cl. 139—267)

1

The present invention relates to a thread cutting and clamping mechanism of the type employed in a loom in connection with a filling transfer motion for cutting the filling end on an exhausted bobbin prior to a transfer operation and for clamping the severed filling end extending to the cloth.

In looms of the general fly shuttle type, when replenishing of filling is indicated, the outgoing or spent filling end extends from the cloth selvage through the eye of the shuttle to the bobbin contained in the shuttle. When the fresh bobbin of filling is inserted in the shuttle, not only must the spent bobbin be removed, but the shuttle eye must be cleared of the spent filling to allow the filling from the fresh bobbin to be threaded properly in said eye. To accomplish this, the filling extending from the selvage of the cloth must be cut as closely as possible to the shuttle, so that the spent bobbin, in being ejected, will draw the short length of filling left extending from the shuttle through the shuttle eye, leaving said shuttle eye entirely clear and free. The spent filling end is not only severed near the shuttle, but is clamped near the severed end, so that it may be withdrawn out of the range of the weaving instrumentalities simultaneously with the transfer operation and held in this withdrawn position until the temple cutter cuts it close to the selvage. Usually the shuttle with the new bobbin makes at least two traverses before the temple cutter severs the spent end. There is accordingly provided in such looms a movable blade carrier having severing and clamping blades mounted in front of the shuttle box at the transfer side of the loom. These blades are moved by the carrier to filling receiving position, i. e. rearwardly of the loom toward the shuttle box, prior to each transfer operation and are withdrawn forwardly from such position simultaneously with the transfer operation.

One object of the present invention is to provide a new and improved thread cutting and clamping mechanism for a loom which is more positive in action than prior art mechanisms, which is comparatively simple in construction and highly effective in operation and which lends itself to various adjustments by simple manipulation.

Various other objects of the invention will be apparent from the following particular description and from an inspection of the accompanying drawings, in which:

Fig. 1 is a top plan view of the filling transfer side of a loom and shows a thread cutting and clamping mechanism embodying the present in-

2

vention and indicated in operative position after initiation of transfer;

Fig. 2 is a detail view of a part of the thread cutting and clamping mechanism taken approximately along the lines 2—2 of Fig. 1;

Fig. 3 is a section of the thread cutting and clamping mechanism taken approximately along the lines 3—3 of Fig. 1, but showing this mechanism in inoperative position prior to initiation of transfer;

Fig. 4 is a section similar to that of Fig. 3, but shows the mechanism after transfer has been initiated and after the cutting and clamping blades have been moved rearwardly of the loom and into open operative position in the shuttle box;

Fig. 5 is a section similar to that of Fig. 3, but shows said mechanism after the cutting and clamping blades have been closed and after completion of transfer;

Fig. 6 is a section of the thread cutting and clamping mechanism taken approximately along the lines 6—6 of Fig. 1 and shows the mechanism after transfer has been initiated and while the cutting and clamping blades are being moved rearwardly of the loom towards the lay and are in open operative position and in a phase just prior to that shown in Fig. 4;

Fig. 7 is a detail view of a part of the thread cutting and clamping mechanism taken approximately along the lines 7—7 of Fig. 6;

Fig. 8 is a detail section of the pivot mounting for the blade opening cam taken along the lines 8—8 of Fig. 6;

Fig. 9 is a section similar to that of Fig. 6, but shows the mechanism after the cutting and clamping blades have been closed and in a phase later than that shown in Fig. 5;

Fig. 10 is a detail view of the cutting and clamping blades in closed position taken approximately along the lines 10—10 of Fig. 9;

Fig. 11 is a detail view of the cutting and clamping blades in closed position taken approximately along the lines 11—11 of Fig. 10; and

Fig. 12 is a detail view of the cutting and clamping blades in closed position taken approximately along the lines 12—12 of Fig. 10.

Referring to the drawings, and especially to Fig. 1, the loom to which the present invention is applicable is shown for the purposes of illustration comprising a loom frame having a right loomsides 10 with parallel upright frame webs 11 and 12 interconnected and braced in any suitable manner. Supported on this right loomsides 55 is a rotatable hopper or magazine (not shown) of

the transfer mechanism mounted on a stand 14, having its base 15 secured in position with respect to said loomside by studs or bolts 16. The hopper carries reserve bobbins (not shown) in an annular series and may be of any suitable construction.

The loom comprises the usual lay 17 reciprocable forwardly and rearwardly therealong and carrying on its right side underneath the hopper, the usual shuttle box 18 provided with a bottom opening 19 for the ejection therethrough of an exhausted filling bobbin 20 from a shuttle 21. The front plate 22 of the shuttle box 18 has an opening 23 located adjacent to the shuttle eye 24 when the shuttle 21 is properly boxed in the shuttle box 18. The opening 23 extends along the front shuttle box plate 22, slopes upwardly towards the left side of the loom and is open at its left hand end to permit the severed clamped filling thread to be cleared from the shuttle box 18, as said box moves rearwardly with the lay 17 after thread severing and clamping operations.

The shuttle 21 has the usual cut-away portion or slot 25 in the front wall thereof adapted to be in partial registry with the opening 23 of the front shuttle box plate 22, when the shuttle is properly boxed so that when the thread cutter is in its operative rearward position and the cutting and clamping blades (to be described) extend through said opening and through said slot and are open, the outgoing filling end will rest between said blades ready to be cut and clamped.

The operation of the transfer mechanism is controlled by a starting rod 30 suitably supported near one end in journals 31 on the right loomside 10 and near the other end in journals (not shown) on the left loomside or on the forward side of the breast beam (not shown). The transfer mechanism with its starting rod 30 may be, as far as certain aspects of the invention are concerned, of the usual or of any suitable type.

Whenever the substantial exhaustion of the filling is indicated by a feeler mechanism (not shown), a partial revolution is given to the starting rod 30 to set the transfer mechanism for operation.

The operation of the transfer mechanism is initiated by the starting rod 30, but is controlled by a shuttle feeler operable to revoke automatically the call for transfer when the shuttle 21 is not in proper position in the shuttle box 18 for bobbin transfer. The shuttle feeler for that purpose is of the type shown in copending application Serial No. 147,482, filed March 3, 1950, and comprises a tubular guide 40 secured to a bracket (not shown) affixed to and depending from the base 15 of the hopper stand. Slidable in the guide 40 is a feeler plunger 41 carrying a feeler tip 42. A pin 43 extending through the feeler plunger 41 and through diametrically opposed elongated slots (not shown) in the guide 40 is engaged at its outer projecting ends by the forked prongs of a shipper arm 45 affixed to a suitably journalled pivot shaft 46. The shipper arm 45 is operated from starting rod 30 upon receiving a call for transfer, to move the shuttle feeler tip 42 into position just ahead of the tip of the properly boxed shuttle 21. If the shuttle 21 is not properly boxed, the feeler tip 42 will engage the shuttle and will be moved forwardly of the loom by the forward movement of the lay 17, thereby revoking the call for transfer.

The shipper arm 45 is operated from the starting rod 30, and for that purpose, said starting rod has rigidly connected thereto a crank arm 50

pivotedly connected at its outer end to one end of a link 51, the other end of said link being connected at 52 to said shipper arm. For effecting protection through operation of the shuttle feeler, the link 51 is of the giveaway or lost motion type to transmit motion to the shipper arm 45 about its pivot support when transfer is indicated and the starting rod 30 has been partially rotated and to yield without disturbing the rotative position of said starting rod when protection is indicated by the improper boxing of the shuttle 21.

For effecting transfer of the lowermost filled bobbin on the hopper, there is provided a main 15 transfeerer (not shown) comprising a pivoted arm and a shoe or head on said arm adapted to engage the heel or butt of said bobbin and push said bobbin into the shuttle 21 for transfer action. There is also provided an auxiliary transfeerer 20 comprising an arm (not shown) having a head adapted to engage the filled bobbin to be transferred near its tip and operable in unison with the main transfer arm to effect ejection of the bobbin free from tilting. The auxiliary transfer 25 arm is secured to and transversely of a hollow shaft (not shown) mounted for rocking movement on a hollow bearing or axle rod 53 affixed at one end to a support 54 integral or otherwise rigid with the hopper stand base 15. The hollow shaft 30 is rocked in unison with the main transfer arm to effect simultaneous bobbin transfer operations of the main and auxiliary transfeerers. This construction forms per se no part of the present invention and is fully disclosed and claimed in 35 copending application Serial No. 147,482, filed March 3, 1950.

The cantilever rod 53 extends substantially parallel to the breast beam (not shown) or lay 17 and at its outer unsupported end 55 carries the 40 thread cutter 56. This thread cutter comprises a blade carrier 57 located in front of the shuttle box 18 and directed for forward and rearward movement by a guide 58 having a split clamp 61 adjustably attached to the hollow axle rod 53 by a stud 62. The guide 58 has a T-slot 63 along its lower section and the blade carrier 57 has a corresponding T-head 64 at its upper section extending with a slide fit into said slot.

Upon the initiation of transfer, the blade carrier 57 is moved rearwardly through the starting rod 30 into operative position at the same time the shuttle feeler plunger 41 is moved rearwardly by said starting rod into shuttle feeler position. To that end, the pivot shaft 46 to which the shipper arm 45 for operating the feeler plunger 41 is affixed projects beyond the side of said shipper arm and has pinned or otherwise affixed to the projecting part of said shaft one end of an arm 65 (Figs. 1 and 2), the other end being secured to one end of a push-pull cable 66. The cable 66 extends through a tubular flexible casing 67 and at its other end is secured to the slidable blade carrier 57 by a spring-connection to be described. In this manner, when the starting rod 30 is rotated partially, the resulting angular movement of the shipper arm 45 causes lengthwise movement of the cable 66 and the corresponding movement of the blade carrier 57 rearwardly towards the shuttle box 18 and into operative position.

The cable casing 67 is secured at one end on the hopper stand 14 by means of a clamping nipple 70 held in position by means of lock nuts 72 on a flange 71 forming part of said stand and 75 is secured at its other end to the blade carrier

guide 58 in any suitable manner, as for example by means of a clamping collar 73. The cable casing serves not only to protect the cable 66 therein, but as a guide for said cable in its push-pull operations.

For securing one end of the cable 66 to the blade carrier 57, said cable at this end extends into a hollow 75 (Figs. 3, 4 and 5) in the guide 58 and has secured thereto an anchor rod 76. One end section 77 of the anchor rod 76 is hollow to embrace the end section of the cable 66 with a gripping fit, and the other end is solid and of reduced diameter and passes with a slide fit through a lug 78 integral or otherwise rigid with the guide 58. A collar 80 on the cable 66 serves as an abutment for one end of a coil spring 81 encircling the anchor rod 76, the other end bearing against one side of the lug 78. Nuts 82 threaded on the outer end of the anchor rod 76 and bearing against the other side of the lug 78 limit the movement of said rod endwise in one direction against the expansive action of the coil spring 81.

The blade carrier 57 fixedly mounts a pair of spaced blades 90 and 91 and movably supports a blade 92 therebetween. The fixed blade 90 is a thread cutting blade of rigid material such as metal and has a cutting edge 93 slanting upwardly and rearwardly and bevelled downwardly towards the movable blade 92, as shown in Figs. 10, 11 and 12. The other fixed blade 91 is a thread clamping blade and comprises a board or layer 94 of fiber or similar comparatively soft material to prevent shearing of the yarn, secured to a backing plate 95 made of rigid material such as metal. The movable blade 92 made of rigid material such as metal has a square edge 96 and cooperates with the fixed blade 90 to cut the yarn and cooperates with the other fixed blade 91 to clamp or hold the yarn.

For mounting the different blades 90, 91 and 92 on the blade carrier 57 in position, there is provided a pivot bolt 100 passing through the fixed blades 90 and 91 and a frame part of the blade carrier, and having an intermediate smooth section passing through the movable blade 92 with a snug rotative fit to serve as a pivot support for said latter blade.

A pin 105 (Figs. 6 and 9) secured to a frame part of the blade carrier 57 passes through the blades 90 and 91 with a snug slide fit and cooperates thereby with the pivot bolt 100 to fixedly support said blades on said carrier. An intermediate section of the pin 105 passes through a hole 106 in the movable blade 92 with enough clearance to permit angular movement of said blade about the axis of its pivot support 100.

The blades 90, 91 and 92 are yieldably pressed together by a bolt 103 passing through the blades 90 and 91 with a snug slide fit and through the movable blade 92 with clearance and urged endwise by a coil spring 104 encircling a projecting part of said bolt.

For operating the movable blade 92 in open or closed position with respect to the other blades 90 and 91 at the proper time, there is provided a blade opening cam 110 and a blade closing cam 111 pendulously supported on a bracket plate 112, which in turn is adjustably secured to one side wall 113 of the blade carrier guide 58. The plate 112 is secured to the side wall of the guide 58 by means of bolts 114 and is spaced therefrom by means of spacer sleeves 115 through which said bolts pass.

To permit substantially horizontal adjustments

in position of the cam supporting plate 112, the side wall 113 of the guide 58 is provided with a substantially horizontal slot 116 through which the plate mounting bolts 114 pass. The bolts

5 114 are desirably of the carriage type with shanks of square cross-section retained in the slot 116 in the side wall 113 of the guide 58, to prevent the turning of said bolts when the nuts are screwed thereon.

10 The tail end of the movable blade 92 carries an axle pin 119 on which is rotatably supported a cam follower roller 117 adapted to ride over the blade operating cams 110 and 111.

15 The blade opening cam 110 is disposed below the course of slide travel of the movable blade 92 and is supported on a pin 118 to swing freely therefrom under the action of gravity and the action of the follower roller 117. To permit the blade opening cam 110 to be adjusted vertically

20 independently of the blade closing cam 111, the pin 118 is in the form of an eccentric bolt, as shown in Fig. 8, and has a slotted head 120 slotted to receive a turning tool, an end journal 121 having a bearing in the plate 112, and an eccentric 25 122 between said head and said journal supporting the blade opening cam 110 for free swinging movement. A nut 123 is threaded on the projecting end of the bolt pin 118 to retain the pin against endwise movement and to lock said pin in rotative adjusted position.

30 The blade closing cam 111 is disposed above the course of slide travel of the movable blade 92 and is supported on a pin 130 to swing freely therefrom under the action of gravity and the 35 action of the follower roller 117. The pin 130 is of the eccentric type similar to that of the pin 118 to permit the blade closing cam 111 to be adjusted vertically independently of the blade opening cam.

40 The blade opening cam 110 is disposed in front of the blade closing cam 111 in relation to the loom and has an upper cam edge 131 inclined upwardly towards the rear of the loom, as shown in Figs. 3, 4, 5 and 6, when said cam hangs freely 45 downwardly by gravity. A stop 132 on the plate 112 limits counterclockwise rotation of the blade opening cam 110, while the roller 117 on the movable blade 92 is riding over its inclined cam edge 131 during the rearward movement of the blade carrier 57 towards the shuttle box 18 resulting from a pushing of the cable 66.

The blade closing cam 111 has a lower cam edge 134 inclined upwardly towards the rear of the loom, as shown in Fig. 9, when said cam hangs freely downwardly by gravity. A stop 135 on the plate 112 limits counterclockwise rotation of the blade closing cam 111, while the roller 117 on the movable blade 92 is riding over its inclined cam edge 134 during forward movement (towards the right in Fig. 9) of the blade carrier 57 resulting from the pushing action of the shuttle box 18 on said blade carrier in its movement towards front center position, as will be described.

55 To move the blade carrier 57 in a forward direction (towards the right in Fig. 9) to close the blade 92 for thread cutting and clamping operations, the carrier has a lug 137 (Figs. 1, 3, 4 and 5) into which is threaded a stud 138 extending towards the shuttle box 18 on the lay 17. The head of the stud 138 is in the path of forward movement of a bunter 139 on the front shuttle box plate 22 and when engaged thereby, as shown in Fig. 4, the blade carrier 57 is moved forwardly therewith to effect closing of the blade 70 92. The stud 138 can be adjusted on the blade

carrier 57 and is locked in an adjusted position by a nut 140.

Operation

Although the operation of the thread cutting and clamping device is believed apparent from the foregoing description, it is summarized herein.

During normal operation, when no transfer is indicated, the starting rod 30 is in inactive rotative position, and the feeler plunger 41 is in withdrawn position with respect to the shuttle box 18. During this normal operation, the cable operating arm 65 is in the position shown in dot and dash lines in Fig. 2, and the blade carrier 57 will be in the withdrawn inactive position shown in Fig. 3, with the blade 92 in closed position, the cam follower roller 117 in position forwardly beyond the lower cam 110, and said lower cam hanging downwardly and against the stop 132.

When transfer is indicated by filling feeler motion on the left side of the loom, the starting rod 30 is partially rotated, causing the shipper arm 45 to swing angularly and the shuttle feeler plunger 41 to move into extended feeler position shown in Fig. 1. At the same time, the arm 65, through the operation of the pivot shaft 46 of the shipper arm 45 will be shifted from the position shown in dot and dash lines in Fig. 2 to the position shown in full lines. This operation will push the cable 66 and will cause thereby the blade carrier 57 to be moved along the guide 58 towards the shuttle box 18 on the lay 17, as shown in Fig. 4, and towards the left, as shown in Fig. 6. While the blade carrier 57 is moving towards the shuttle box 18, the follower roller 117 on the movable blade 92 riding over the inclined cam edge 131 of the lower cam 110, causes said blade to move angularly counterclockwise (Fig. 6) about the pivot support 100 into open position, as shown in dot and dash lines in Fig. 6. The cam 110 is held against rotation during this operation by the stop 132. When the cam follower roller 117 reaches the end of the inclined cam edge 131, it comes into engagement with the upper cam 111 and swings that cam clockwise out of the way, as shown in full lines in Fig. 6. The upper cam 111 swinging idly clockwise as described does not move the blade 92 into closed position, since the pressure of the spring 104 prevents this.

The blade carrier 57 continues its movement towards the shuttle box 18 on the lay 17 (towards the left in Fig. 6), until the upper cam 111 is freed and falls by gravity into position against the stop 135.

While the blade carrier 57 is approximately in the rearward position shown in Fig. 6 and the blade 92 is in the open position indicated, the lay 17 on its forward beat-up movement will cause the blades 90, 91 and 92 to pass through the openings 23 and 25 in the front shuttle box plate 22 and shuttle 21 respectively and to locate the filling end A between the movable blade 92 on the one side and the fixed blades 90 and 91 on the other side, as shown in Fig. 4. As the lay 17 continues its forward movement, the bunter 139 on the front shuttle box plate 22 engages the head of the stud 138, as shown in Fig. 5, and moves therewith the blade carrier 57 forwardly (towards the left in Fig. 5) along the guide 58, without disturbing the cable 66. The lost-motion spring connection 81 permits this forward movement of the blade carrier 57.

As the blade carrier 57 moves forward with

the shuttle box 18, the cam follower roller 117 riding over the inclined cam edge 134 of the upper cam 111 moves the blade 92 angularly about its pivot support 100 into closed position, as shown in Figs. 5 and 9. This operation clamps the filling end between the blades 91 and 92 and cuts the filling end between the blades 90 and 92. Immediately after the closing of the blade 92, the transfer of a reserve bobbin from the hopper to the shuttle 21 and simultaneous ejection of the exhausted bobbin through the box opening 19 takes place.

The forward movement (towards the right in Fig. 9) of the blade carrier 57 is continued until the follower roller 117 clears the upper cam 111 and engages the lower cam 110. This lower cam 110 swings idly clockwise (Fig. 9) about its pivot support 118 as the follower roller 117 moves along said cam, until said roller moves beyond said cam into position shown in Fig. 3. The lower cam 110 released thereby will swing down by gravity against the stop 132 in position to move the blade 92 into open position, upon the next transfer indication.

After the lay 17 reaches front center position, it begins its rearward movement, thereby causing the severed clamped end of the filling A to be pulled out through the opening 23 in the front shuttle box plate 22 and to be withdrawn out of the range of the weaving instrumentalities. During this rearward movement of the lay 17, the starting rod 30 is returned to its normal rotative position. This causes the cable operating arm 65 to return to the position shown in dot and dash lines in Fig. 2, and the cable 66 to be pulled. The blade carrier 57 is thereby withdrawn into the inactive forward position shown in Fig. 3, until the next transfer operation. While in this inoperative position and while the severed filling end is held between the closed blades 91 and 92, the filling is severed near the cloth selvage by the usual temple thread cutter (not shown) and will be released from said blades, when these blades are again opened during the next thread cutting and clamping operation, upon the next indication of transfer.

If after transfer is initiated, the shuttle feeler plunger 41 is moved forward by an improperly boxed shuttle, this revokes the call for transfer and also causes the cable 66 through the arm 67, to return the blade carrier 57 into inactive position shown in Fig. 3.

While the invention has been described with particular reference to a specific embodiment, it is to be understood that it is not to be limited thereto, but is to be construed broadly and restricted solely by the scope of the appended claims.

What is claimed is:

60. 1. In a loom having a starting rod which is partially rotated when transfer is indicated, a bobbin transfer mechanism, a transmission between said starting rod and said transfer mechanism for initiating the operation of said transfer mechanism upon partial rotation of said starting rod resulting from a transfer indication, a thread cutter, and a cable connection between a movable part of said transmission and said thread cutter for operating said thread cutter upon operation of said transfer mechanism.

65. 2. In a loom having a starting rod which is partially rotated when transfer is indicated, a bobbin transfer mechanism including a shuttle feeler, a transmission between said starting rod

70

and said shuttle feeler for actuating said shuttle feeler into operative position and including a shipper arm and a pivot shaft mounting said arm, a thread cutter, an arm secured to said pivot shaft, and a push-pull cable between said latter arm and said thread cutter, for operating said thread cutter upon operation of said transfer mechanism.

3. In a loom having a lay with a shuttle box near the bobbin transfer side of said loom for receiving a shuttle, a shuttle feeler located in a region near one end of the shuttle when properly boxed, means for operating said shuttle feeler, a thread cutter located in a region near the other end of the shuttle when properly boxed, and a cable connection between a movable part of said feeler operating means and said thread cutter for operating said thread cutter upon operation of said shuttle feeler.

4. In a loom having a lay, a bobbin transfer mechanism, a thread cutter including a blade carrier movable into and out of thread cutting position with respect to a boxed shuttle, a pair of relatively movable thread cutting blades on said carrier, a transmission between said transfer mechanism and said blade carrier for moving said carrier in one direction into operative cutting position with respect to the boxed shuttle automatically in accordance with the operation of said transfer mechanism, said blade carrier being disposed in position to be moved by the motion of said lay in the opposite direction after said blade carrier has been moved into operative position, said transmission including a cable and a lost-motion connection to permit the movement of said blade carrier in said opposite direction without disturbing said cable, and means operable by the movement of said blade carrier in said opposite direction for moving said blades relative from open thread receiving position into closed thread cutting position.

5. In a thread cutting mechanism for a loom having a lay supported shuttle box, a blade carrier, means for guiding said carrier for movement towards and away from the shuttle box into and out of operative position, a pair of thread cutting blades on said carrier, one of said blades being mounted for movement into and out of thread cutting position with respect to the other blade, cam means in the path of movement of said movable blade for operating said movable blade into and out of thread cutting position as said blade carrier is moved, and means mounting said cam means for positional adjustments of said cam means.

6. In a thread cutting mechanism for a loom having a lay supported box, the combination as described in claim 5, said mounting means permitting vertical and horizontal adjustments in the position of said cam means.

7. In a thread cutting mechanism for a loom having a lay supported shuttle box, a blade carrier, means for guiding said carrier for movement towards and away from the shuttle box into and out of operative position, a pair of thread cutting blades on said carrier, one of said blades being mounted for movement into and out of thread cutting position with respect to the other blade, a bracket, means supporting said bracket, and means supported on said bracket and disposed in the path of movement of said movable blade for operating said movable blade into and out of thread cutting position as said blade carrier is moved, said bracket supporting means being adjustable to permit ad-

justments in the position of said blade operating means with respect to said movable blade.

8. In a thread cutting mechanism for a loom having a lay supported shuttle box, a blade carrier, means for guiding said carrier for movement towards and away from the shuttle box into and out of operative position, a pair of thread cutting blades on said carrier, one of said blades being mounted for movement into and out of thread cutting position with respect to the other blade, a bracket plate, means supporting said bracket plate for positional adjustment along one direction, means disposed in the path of movement of said movable blade for operating said movable blade into and out of thread cutting position as said blade carrier is moved, and means supporting said blade operating means on to said bracket plate for positional adjustment thereon along a direction crosswise of said first mentioned direction.

9. In a thread cutting mechanism for a loom having a lay supported shuttle box, a blade carrier, means for guiding said carrier for movement towards and away from the shuttle box into and out of operative position, a pair of thread cutting blades on said carrier, one of said blades being mounted for movement into and out of thread cutting position with respect to the other blade, a bracket plate, elongated slot and bolt means for supporting said bracket plate on to said guiding means for horizontal adjustment, cams disposed in the path of movement of said movable blade for operating said movable blade into and out of thread cutting position as said blade carrier is moved, and eccentric pivot means for supporting each of said cams on to said bracket plate for vertical adjustment thereon.

10. In a thread cutting mechanism for a loom having a lay supported shuttle box, a blade carrier, means for guiding said carrier for movement towards and away from the shuttle box into and out of operative position, a pair of thread cutting blades on said carrier, one of said blades being mounted for movement into and out of thread cutting position with respect to the other blade, a member in the path of movement of said movable blade adapted to move said latter blade into open thread receiving position with respect to the other blade, as said blade carrier moves in one direction, and a separate member in the path of movement of said movable blade adapted to move said latter blade into thread cutting position with respect to the other blade, as said blade carrier moves in the opposite direction.

11. In a thread cutting and clamping mechanism for a loom having a lay supported shuttle box, a blade carrier, means for guiding said carrier for movement towards and away from the shuttle box into and out of operative position, a pair of blades fixedly mounted on said carrier, a third blade pivotally mounted on said carrier for movement into and out of thread cutting and clamping position with respect to said fixedly mounted blades, a cam in the path of movement of said movable blade towards said shuttle box for camming said movable blade into open thread receiving position with respect to the other blades, and a second cam in the path of movement of said movable blade away from said shuttle box for camming said movable blade into closed thread cutting and clamping position with respect to the other blades.

12. In a thread cutting and clamping mechanism for a loom having a lay supported shuttle

11

box, a blade carrier, means for guiding said carrier for movement towards and away from the shuttle box into and out of operative position, a pair of blades fixedly mounted on said carrier, a third blade pivotally mounted on said carrier for movement into and out of thread cutting and clamping position with respect to said fixedly mounted blades, a cam follower mounted on said movable blade, a cam in the path of movement of said movable blade towards said shuttle box pivotally supported and having a cam surface over which said cam follower is adapted to ride when said blade carrier is moving towards said shuttle box, to cam said movable blade into open thread receiving position with respect to the other blades, stop means for holding said cam against pivotal movement in one angular direction while said cam is moving said movable blade into open position with respect to the other blades, said cam being free to swing about its pivot axis in the opposite angular direction to permit said cam follower to move idly past said cam when said blade carrier is moved away from said shuttle box, a second cam in the path of movement of said movable blade away from said shuttle box pivotally supported and having a cam surface over which said cam follower is adapted to ride when said blade carrier is moving away from said shuttle box, to cam said movable blade into closed thread cutting and clamping position with respect to the other blades, and stop means for holding said second cam against pivotal movement in one angular direction while said second cam is moving said movable blade into closed position with respect to the other blades, said second cam being free to swing about its pivot axis in the opposite angular direction to permit said cam follower to move idly past said second cam, when said blade carrier is moved towards said shuttle box.

13. In a thread cutting and clamping mech-

12

anism for a loom having a lay supported shuttle box, the combination as described in claim 12, comprising a bracket plate mounted on said guide, and an eccentric pin pivotally supporting each of said cams on said plate and adjustable to effect adjustments in the location of the pivot axis of each cam with respect to the other cam.

14. In a thread cutting and clamping mechanism for a loom having a lay supported shuttle box, the combination as described in claim 12, comprising a bracket plate mounted on said guide, said cams being pivotally mounted on said plate, and the cam follower carried by said movable blade being in the form of a roller.

15. In a thread cutting and clamping mechanism for a loom having a lay supported shuttle box, a blade carrier having a slide head, a fixed guide with a groove for receiving said head to guide said blade carrier in its movement towards and away from said shuttle box, thread cutting and clamping blades supported on said carrier and movable relatively into and out of thread cutting and clamping position, a cable attached to said blade carrier and operable from a bobbin transfer mechanism to move said carrier towards and away from said shuttle box, and means operable by the movement of said blade carrier for moving said blades relatively into or out of thread cutting and clamping position.
